(57) **CLAIM**

The ornamental design for a vehicle body side, as shown and described.

DESCRIPTION

FIG. 1 is a perspective view of a vehicle body side according to a first embodiment showing my new design;

FIG. 2 is a front view thereof;

FIG. 3 is a rear view thereof;

FIG. 4 is a right view thereof;

FIG. 5 is a left view thereof; and

FIG. 6 is a top view thereof.

FIG. 7 is a perspective view of a vehicle body side according to a second embodiment showing my new design;

FIG. 8 is a front view thereof;

FIG. 9 is a rear view thereof;

FIG. 10 is a left view thereof;

FIG. 11 is a right view thereof; and,

FIG. 12 is a top view thereof.

The broken lines in the drawings illustrate portions of the vehicle body side that form no part of the claimed design.

1 Claim, 10 Drawing Sheets
